UNITED STATES PATENT OFFICE.

WILLIAM J. GALT, JR., OF PHILADELPHIA, PENNSYLVANIA, ASSIGNOR TO THE DE LONG HOOK AND EYE COMPANY, OF PHILADELPHIA, PENNSYLVANIA, A CORPORATION OF PENNSYLVANIA.

GARMENT-HOOK.

1,201,817.

Specification of Letters Patent. Patented Oct. 17, 1916.

Application filed September 5, 1913. Serial No. 788,210.

To all whom it may concern:

Be it known that I, WILLIAM J. GALT, Jr., a citizen of the United States, residing in Philadelphia, county of Philadelphia, State 5 of Pennsylvania, have invented certain new and useful Improvements in Garment-Hooks, of which the following is a specification.

My invention relates to garment hooks of 10 the character which are most generally secured to the garment or other fabric by means of threads which pass through thread eyes at one end of the shank of the hook and also by means of threads which extend 15 around the shank of the hook at a point adjacent to the bend between the shank and bill of the hook, such threads being also in engagement with the material to which the hook is fastened. Unless some means is provided 20 to prevent such action the shank of the hook is liable to, and in practice does, slide forward underneath the last-mentioned threads so that the material adjacent to or against the underneath side of the 25 shank of the hook becomes puckered and uneven. Of course, the same result would be effected if the hook remained stationary and the material of the garment or other article moved with relation to the hook toward 30 the thread eyes. Inventors and mechanics familiar with this objection have sought in various ways to provide means to overcome this objection, but thus far without that degree of success which is satisfactory 35 from a practical standpoint.

It is the object of my invention to meet this objection and overcome the same by the provision of means which does not affect in any substantial manner the appearance of 40 the hook as already manufactured and which does not necessitate the formation of projections upon the outside of the hook and thereby make the same appear larger or more bulky.

To effect the result which I have sought 45 to accomplish I have provided in what is known as the central spring stop wire of a hook a bend or loop which is adapted to serve as a stop to prevent relative backward 50 movement of the threads at the front end

of the shank of the hook so that the material intermediate the thread eyes and the front end of the shank of the hook is maintained in fixed or constant relation with respect to the shank of the hook.

55

In the accompanying drawing, I have illustrated one form of a convenient embodiment of my invention, but it will be understood that changes in the details of construction may be made within the scope of 60 the claims without departing from my invention.

In the drawings:—Figure 1 is a side elevation of a hook embodying my invention and showing a portion of an eye in engagement therewith and also showing the hook attached to a sheet of fabric; Fig. 2 is a top plan view of the hook shown in Fig. 1; Fig. 3 is a sectional view taken on the line 3—3 of Fig. 1; and Fig. 4 is a sectional view taken on the line 4—4 of Fig. 2.

In the drawings and specification I have illustrated and described the hook in which my invention is embodied as constructed of wire, but it will be understood that the hook 75 may be constructed of any other suitable material.

Referring to the drawings, 1 and 2 designate the shank wires of the hook and 3 and 4 the thread eyes at the rear end of the 80 shank. These wires 1 and 2 are extended to form the bill 5 of the hook in well known manner. One end of the wire of which the hook is constructed terminates at 6 as shown in Figs. 2 and 3. The other end of the wire 85 is extended from one of the thread eyes, as indicated at 7, upwardly toward the bill of the hook to form a spring stop 8 to prevent accidental disengagement of the eye 9^a therefrom.

90

The central spring wire is extended forwardly and downwardly to the point 9 at which it is bent laterally toward the outer side of the shank wire 1 and is then bent again laterally transversely or across and above the said wires 1 and 2, as indicated at 10, and then rearwardly, as indicated at 11, and then downwardly and forwardly, as indicated at 12, to a position between the forward ends of the shank wires 1 and 2 from 100

which point it is extended forwardly around the bend of the hook and to a point 13 within the bill thereof. The hook is secured to the fabric of a garment or to any other suitable material by means of stitches 14 through the thread eyes and stitches 15 which extend around the forward portion of the shank of the hook, between the same and the bill of the hook. As will be seen upon an inspection of Fig. 1 of the drawings, these stitches are situated underneath the bend 9, 10, 11 of the central wire of the hook. It is apparent, therefore, that it is impossible for the hook to be moved forward with respect to the fabric 16 to which it is connected and that the hook is held in fixed relation to that portion of the material intermediate the threads 14 and 15 and that such material within this region is held smooth and even.

It will be apparent also from an inspection of the drawings that the threads 15 are protected against abrading or wearing action of eyes, such as the eye 9^a, which may be in engagement with the hook. The overlying bend 9, 10, 11 also prevents the wearing out or abrading of the threads 15 from any other cause.

It is preferred that the width of the bend 9, 10, 11 should not be greater than the width of the shank of the hook or of the bill of the hook at the region where such bend occurs. By this means the neatness of the hook is not affected and yet the efficiency of my invention, for the purpose for which it is intended, is obvious and apparent. Furthermore, the presence of the bend 9, 10, 11 in the spring wire having formed therein the stop 8, does not affect the resiliency of said stop but on the contrary adds to such resiliency which is a substantial advantage from the standpoint of practicability.

I claim:

1. A garment hook consisting of wire bent to form shank and bill portions and a portion situated intermediate said shank and bill portions which intermediate portion is spaced from the said shank portion and at a point in proximity to the bend between the shank and bill portion is bent and extended rearwardly and downwardly intermediate said shank and bill portions and is then bent and extended forwardly and downwardly to a position intermediate the wires 55 of the shank portion.

2. A garment hook having shank and bill portions which consist respectively of a plurality of wires arranged in adjacent relation with respect to each other, the said shank and bill portions being connected by bends of the said wires, and a wire spring stop intermediate the shank and bill portions, the wire forming said stop being extended downwardly and forwardly toward

the bend between the shank and bill portions of the hook and then extended laterally in one direction, then transversely, rearwardly and downwardly across the shank wires of the hook, and then downwardly and forwardly to a position between the shank 70 wires, and thence around the bend and into the space between the wires forming the bill of the hook.

3. A garment hook consisting of a wire bent to form the shank and bill portions of 75 the hook, the wires of said portions being arranged in general parallel relation with respect to each other and being connected by intermediate bends and a portion of the wire being extended from the rear of the 80 shank upwardly toward the bill of the hook and then forwardly and downwardly therefrom to a point above the plane of the shank wires and adjacent to the bend between the shank and bill portions of the hook, the said 85 wire then being bent transversely of the shank wires and then extended downwardly and forwardly to a position between the said wires, the said bend being spaced from the said shank wires for the purpose stated. 90

4. A garment hook consisting of wire bent to form the shank and bill portions, the said portions being connected by a bend, the said hook being provided with thread eyes at one end of the shank and having a portion 95 extended upwardly from a point adjacent to the thread eyes toward the bill of the hook and then forwardly and downwardly to form a spring stop, the forward end of the said downwardly extended portion being 100 bent transversely of the said shank wires and extended rearwardly and then downwardly and forwardly to a position between the shank wires, the wire forming the said 105 bend being situated above the shank wires to form a space for attaching means extending around the shank wires at a point adjacent to the bend between the shank and bill portions of the hook.

5. A garment hook comprising shank and 110 bill portions of wires and having thread engaging and protecting means intermediate said portions, the said means comprising a wire bent laterally between the shank and bill portions to form a loop opening toward the 115 connecting bend between the shank and bill portions, a portion of said loop being situated above the shank portion and the end portion of said wire extending forwardly between portions of the wires of the shank 120 and bill portions.

6. A garment hook consisting of shank and bill portions and an intermediate part the said part having a loop at its forward end intermediate said portions and extending laterally thereof forming a thread protecting means and stop therefor, the said 125 loop opening toward the bend connecting

said shank and bill portions and one part of the said loop being situated above and extending transversely of a plane extending longitudinally of and at right angles to the 5 plane of the shank to provide a space for the reception of the attaching threads.

In testimony that I claim the foregoing

as my invention, I have hereunto signed my name this fourth day of September, A. D. 1913.

WILLIAM J. GALT, JR.
